UNITED STATES PATENT OFFICE.

EDWARD P. FRAWLEY, OF NEW YORK, N. Y.

DESIGN FOR A DESK-CABINET.

51,640.

Specification for Design.

Patented Jan. 1, 1918.

Application filed October 11, 1917. Serial No. 196,079. Term of patent 14 years.

To all whom it may concern:

Be it known that I, EDWARD P. FRAWLEY, a citizen of the United States, residing in the city of New York, borough of Manhattan, in the county and State of New York, have invented a new, original, and ornamental Design for Desk-Cabinets, of which the following is a specification, reference being had to the accompanying drawings, forming part thereof.

I claim:

The ornamental design for a desk cabinet, as shown.

EDWARD P. FRAWLEY.

Witnesses:

LOUIS G. JACOB,
L. C. JACOB.
